UNITED STATES PATENT OFFICE

104,325

DESIGN FOR A RADIO LAMP

Platt R. Lasseter, Hialeah, Fla.

Application January 16, 1937, Serial No. 67,108

Term of patent 7 years

To all whom it may concern:

Be it known that I, Platt R. Lasseter, a citizen of the United States, residing at Hialeah, in the county of Dade and State of Florida, have invented a new, original, and ornamental Design for a Radio Lamp, of which the following is a specification, reference being had to the accompanying drawing, wherein:

Figure 1 is a front view of a radio lamp, showing my new design.

Figure 2 is a rear view.

Figure 3 is a side view.

I claim:—

The ornamental design for a radio lamp, as shown.

PLATT R. LASSETER.
